ATTORNEYS.

UNITED STATES PATENT OFFICE.

FRANKLIN G. NEUBERT, OF WATERBURY, CONNECTICUT.

BUTTON.

SPECIFICATION forming part of Letters Patent No. 633,888, dated September 26, 1899.

Application filed April 13, 1897. Serial No. 631,964. (No model.)

To all whom it may concern:

Be it known that I, FRANKLIN G. NEUBERT, a citizen of the United States, and a resident of Waterbury, in the county of New Haven 5 and State of Connecticut, have invented certain new and useful Improvements in Buttons, of which the following is a specification.

My invention relates to an improvement in buttons, and more particularly to that kind or 10 class thereof commonly known and referred to as "rivet" or "tack-fastened" buttons—that is, a button adapted to be secured to cloth or fabric by means of a metal tack or fastener—the object of the same being to construct a 15 button of few parts in such a way that it may be easily and readily assembled and cheap to manufacture and adapted when secured in place to withstand the strain imposed upon it.

With these and other ends in view my invention consists of a button constructed of 20 two parts only—viz., a cap having the central portion thereof formed into an anvil or die for upsetting the piercing end of the tack or fastener and a spacer engaging with said 25 anvil or die for separating said cap or face of the button from the cloth or fabric, and also for receiving and retaining the point of the tack or fastener, and thereby hold the button 30 securely to the material.

My invention further consists in certain novel features of formation, as will be hereinafter described, and pointed out in the 35 claims.

In the accompanying drawings, Figure 1 is a 40 sectional view of the face-plate or cap after being partly shaped or formed. Fig. 2 shows the cap or face in its completed form. Fig. 3 is a sectional view of the cap and spacer prior to being assembled. Fig. 4 is a similar 45 view showing the two parts assembled, the fastener and section of the fabric detached. Fig. 5 is a sectional view showing the button after being secured to cloth or fabric.

Referring to the drawings, A represents 50 the face-plate or cap of a button, the outer edge *a* of which may be bent or curled over or under to secure a proper finish and avoid a raw or rough edge thereon. By means of proper dies the central portion of the cap or face A is shaped, first, as shown in Fig. 1—that is, with a depressed center B, a recess *b*

encircling the upper side thereof—and, subsequently, as shown in Fig. 2—that is, with the depressed central portion B in the form of 55 an anvil C, the lower side of which is curved inwardly and toward the face or cap A and forms a die or anvil proper for overturning the piercing end of the metal fastener, the sides *c* of said anvil or die being curved inwardly toward each other for the purpose of retaining the spacer in engagement therewith, as will be hereinafter described.

In Fig. 3 I have shown the spacer D prior to being attached to the cap or face of the 65 button, the upper end of said spacer being open and its lower edge bent inwardly and upwardly for properly receiving and directing the point of the tack or fastener.

In assembling the cap or face of button A 70 and the spacer D the open end of the spacer is slipped over the anvil or die C, and upon striking said spacer a blow or by forcing the two parts together by means of proper tools the upper edge of said spacer D will be forced 75 into the recess *b* in the cap or face of the button, and thereby bent or turned inwardly, causing said spacer to more or less tightly grasp the anvil or die and prevent it from subsequently disengaging itself from said die 80 or anvil.

It will of course be understood that instead of striking the spacer or crowding or forcing it against the cap or face in order to turn the 85 edge of said spacer inwardly, as above described, the edge of said spacer may be rolled inwardly, causing it to more or less tightly grasp or hug the sides of the anvil or die, as in the first instance.

In securing the button to cloth or fabric 90 a metal fastener E, preferably in the form of a tack or rivet, is utilized, which after piercing the cloth or fabric F enters the spacer D, the piercing end of said tack upon being forced or driven against the lower 95 curved side of said anvil curling or upsetting within the spacer, thus tightly securing the button to said cloth or fabric.

From the foregoing it will be understood 100 that my invention is exceedingly simple, the button consisting of two parts—viz., a face and a spacer—the anvil or die being made in one part with said face, and, furthermore, by securing the spacer to the sides of said die or

anvil by curling or rolling the edge of the spacer inwardly the operation of assembling the parts of the button is simply and quickly performed.

5. Having fully described my invention, what I claim as new, and desire to secure by Letters Patent, is—

1. A two-part button constructed with a face-plate having its central portion depressed to form a die or anvil, and a one-piece spacer directly engaging with and secured to said depressed center for separating the face-plate from the cloth or fabric, substantially as described.

15. 2. A button consisting of a face-plate having its central portion depressed and formed into a die or anvil, and a one-piece spacer fitting around said anvil and having its upper

end bent inwardly for holding it in engagement therewith, substantially as described.

3. A button consisting of a face-plate having its central portion depressed and formed into an anvil, the sides of which latter are curved inwardly, and the bottom upwardly, and a one-piece spacer fitting around said anvil, the upper end thereof being bent inwardly for retaining it in engagement therewith, substantially as described.

Signed at Waterbury, in the county of New Haven and State of Connecticut, this 27th day of March, A. D. 1897.

FRANKLIN G. NEUBERT.
